MUFFLER

Joseph P. Marx, Hartford, Wis.

Application January 25, 1945, Serial No. 574,569

11 Claims. (Cl. 181—49)

1

The invention relates to mufflers, and more particularly to an inexpensively constructed silencer especially adapted for use on the exhaust of low velocity internal combustion engines, gas engines, air motors, and the like.

Known types of mufflers designed to silence the noise of the exhaust of an engine embody various conventional types of construction and assembly in which means is provided, usually in the form of axial and surrounding or intermediate tubular passageways, at least some of which are coextensive with the entire length of the muffler, interconnected by louvered perforations intended to create a turbulence in the escaping gases and sound waves as they flow from one passageway to the other. Such prior known devices of a kind that may be adapted for use on low velocity motors are highly inefficient and in some instances totally ineffective as silencers, because of their peculiar internal organization which, in most instances, results in the creation of whistling noises, and their use is therefore not very desirable. Such known mufflers also are objectionable from the standpoint of involved and costly assembly. It is therefore an object of the present invention to provide a very efficient exhaust muffler, particularly useful on low velocity engines, of the kind which is inexpensive to construct and assemble, and which may be installed easily and quickly and embodies a minimum of parts.

Another object of the invention is to provide a muffler with a series of interconnected compartments of a kind having progressively increasing capacities for a portion of the distance traveled by the exhaust gases and sound waves passing therethrough, and progressively decreasing capacities for the remaining distance of travel through said muffler.

Another object is to provide a muffler having chambers equipped with novelty shaped baffles effective to divide said chambers into irregularly shaped compartments communicating one with the other through radial openings in said baffles.

Another object of the invention is to provide a low velocity muffler of a kind which causes the gases and sound waves entering therein to be divided into a multiplicity of turbulent non-directional streams of different values, lengths and velocities so as to absorb and destroy sound waves of all frequencies and provide maximum efficiency in silencing noises.

Another object is to provide a muffler organization embodying novel features of construction.

Other and further objects of the present in-

2

vention will be apparent from the following description and claims and are illustrated in the accompanying drawing which, by way of illustration, shows a preferred embodiment and the principle thereof, and which is considered to be the best mode contemplated for applying that principle. Other embodiments of the invention embodying the same or equivalent principle may be used and structural changes may be made as desired, by those skilled in the art without departing from the present invention and the purview of the appended claims.

In the drawing:

Fig. 1 is a perspective view of the improved silencer.

Fig. 2 is a longitudinal central detail view of the silencer.

Fig. 3 is a transverse sectional detail view taken on line 3—3 of Fig. 2.

Fig. 4 is a transverse sectional detail view taken on line 4—4 of Fig. 2.

The silencer embodying the features of the present invention and disclosed in the accompanying drawing is formed of sheet material, such as sheet steel or metal tubing, and is constructed of a plurality of separate parts, all joined as by welding into an integral self-contained unit having a uniform external appearance. As best illustrated in Fig. 2, the muffler includes a cylindrical shell or body portion, generally indicated at 11, consisting of an intermediate tubular portion 12 and two identical end portions 13. The end portions 13 are each substantially cup-shaped so as to provide a circumferential wall 14 having the same diameter as the wall of the intermediate portion 12, and an end wall 15. The end wall 15 of each end portion is provided with an axial opening suitably flanged externally as at 16, or otherwise formed, to receive a tubular or like fitting for adapting one end of the muffler for attachment to the exhaust of an engine and the other end for the discharge of gases. In the present instance, one of the end portions 13 carries an externally threaded inlet nipple 17 fitted into the flange opening thereof and secured in place as by welding 18, so as to provide an integral leak proof connection. The other end portion 13 has a tubular tail fitting 19 fitted snugly within the flanged opening 15 thereof and firmly secured thereto as by welding at 20.

The margins at the free edges of the circumferential walls 14 of both end portions 13 are flared outwardly to provide an external circumferential flange 21 on each, and the end margins 55 of the intermediate portion 12 similarly are flared

outwardly to provide circumferential external flanges 22. When the end portions 13 are arranged in proper relationship at opposite ends of the intermediate portion 12, the respective complementary external flanges 21 and 22 are brought into registering abutment one with the other, and they are joined together, as by welding, into leak proof circumferential seams 23 to prevent the escape of gases at the joining and to firmly connect the end portions 13 and intermediate portion 12 into a unitary circumferentially reinforced shell structure.

The intermediate portion 12 is fitted with a circular partition wall 24 which may be flanged, as at 25, to fit snugly within said portion. The partition 24 preferably is firmly secured within the intermediate portion 12 as by spot welding 26, and it is preferred that said partition be spaced closer to one end of the intermediate portion for a purpose to be explained presently. It should be noted at this time that the partition wall 24 divides the shell 11 into two chambers of unequal size and that it contains a plurality of port openings 27 so as to afford restricted passageways for the gases from one chamber to the other.

Each of the end portions 13 is provided with a novelly shaped baffle of a kind generally indicated at 28. As shown, each baffle 28 consists of a substantially cup-shaped element including a circumferential wall 29, having a diameter considerably smaller than the inside diameter of the circumferential wall 14 of the end portion 13, an imperforate end wall 31, and an imperforate external circumferential mounting flange 32. The mounting flange 32 is formed with an annular lip 33 having an external diameter of such size as to fit snugly within the end portion 13, so that the baffle 28 may be firmly secured within said end portion as by spot welding 34.

The location of the baffles 28 within the muffler shell 11, with one located on each side of the partition 24, serves effectively to divide each of the chambers hereinabove referred to into two compartments of unequal capacities. More specifically, a compartment 35 is provided immediately adjacent the end of the muffler carrying the inlet nipple 17. This compartment has less capacity than the next adjacent compartment identified at 36, while a compartment 37, located on the other side of the central partition wall 24 has a capacity slightly less than the capacity of compartment 36. Similarly, the end compartment 38, next adjacent the tail fitting 19, has a capacity less than that of the compartment 37, all for a purpose to be explained presently.

The circumferential wall 29 of each of the cup-shaped baffles 28 is provided with suitable apertures 39, preferably in the form of slots, so as to afford connecting passageways between the compartments located on either side thereof.

In use, the nipple 17 is connected in a conventional manner to the exhaust or discharge pipe of the engine to be silenced. The exhaust or discharge gases and attendant sound waves enter the muffler shell 11 through said nipple and expand within the compartment 35. The expanded gases and sound waves then flow under pressure radially through the slotted apertures 39 in the related baffle 28, whereupon they expand further upon entering the next adjacent compartment 36. At this stage of the silencing operation of the muffler, the sound waves are broken up and turbulated to a considerable extent. These expanded exhaust gases and sound waves then flow through the restricted port openings 27, in partition wall

24, and are contracted or compressed slightly upon entering the compartment 37, which is considerably smaller than the compartment 36. The gases and any remaining sound waves then flow radially through the apertures 39 in the related baffle 28 into the last compartment 38 and then out through the exhaust tail-fitting 19 at substantially the same velocity as they entered the muffler.

The initial expansion and subsequent contraction of the exhaust gases and sound waves and the resultant variances in their velocity and directions of travel causes the sound waves to be out of phase one with another. As a result, most of the sound waves are absorbed and destroyed and sound is eliminated from the gases discharged from the muffler through the tail-fitting 19.

I claim:

1. A muffler of the type described, in combination, a cylindrical shell, a flat perforate partition in said shell dividing said shell into two substantially like chambers, each end of said shell having an opening, one communicating with each chamber to provide an inlet and an outlet for exhaust gases and sound waves passing through said chambers, and means in each chamber including a perforate cylindrical wall spaced from the circumferential wall of said shell to deflect the flow of gases and sound waves passing through said chambers.

2. A muffler of the type described, in combination, a cylindrical shell, a perforate partition in said shell dividing said shell into two substantially like chambers, each end of said shell having an opening, one communicating with each chamber to provide an inlet and an outlet for exhaust gases and sound waves passing through said chambers, and means in each chamber including a perforate cylindrical wall spaced from the circumferential wall of said shell to divide each chamber into two compartments each having a different capacity.

3. A muffler of the type described, in combination, a cylindrical shell, a perforate partition in said shell dividing said shell into two chambers, each end of said shell having an opening, one communicating with each chamber to provide an inlet and an outlet for exhaust gases and sound waves passing through said chambers, and means in each chamber including a perforate cylindrical wall spaced from the circumferential wall of said shell to divide each chamber into two compartments wherein one compartment in one chamber has a greater capacity than the corresponding compartment in the other chamber.

4. A muffler of the type described, comprising, a cylindrical shell having inlet and outlet openings at its ends for exhaust gases and sound waves, a perforate flat partition in said shell between said inlet and outlet openings and through which the gases and sound waves must pass, and baffle means on each side of said partition including a perforate cylindrical wall portion spaced from the wall of said shell adapted to deflect the streams of gases and sound waves passing between the partition and one of said openings radially.

5. A muffler of the type described, comprising, in combination, a cylindrical shell having end walls, a tubular fitting in each end wall communicating with the interior of said shell, a perforate partition in said shell dividing the interior of said shell into substantially alike chambers, a cup-shaped baffle having an imperforate external circumferential flange and an imperforate bottom

mounted in each chamber, said flanges being joined to the wall of said shell so as to divide each chamber into compartments, and a plurality of passages in the cylindrical wall of each cup-shaped baffle, the cylindrical walls of said baffles extending in opposite directions and toward the partition.

6. A muffler of the type described comprising, in combination, a cylindrical shell having end walls, inlet and outlet openings for exhaust gases and sound waves in said end walls, a perforate partition in said shell dividing the interior thereof into two cylindrical chambers, short cylindrical members arranged one in each chamber, said members having their cylindrical wall concentric with and spaced from the wall of said shell, an external flange on one end of each member for mounting said member to said shell one closely adjacent to each end wall thereof, and an imperforate wall at the other end of each cylindrical member, said members having their cylindrical walls perforate so as to enable the gases to flow from the inlet to the outlet opening.

7. A shell for a muffler, comprising, two like cylindrical end members each closed at one end and having an external flange on its free edge, said closed ends having reduced openings therein for the passage of exhaust gases and sound waves, an intermediate cylindrical member of like diameter between said end members, an external circumferential flange at each end of said intermediate member to abut the flange on the respective end member, said flanges being joined to prevent separation of the members and to provide circumferential reinforcement for the shell, and a perforate partition in said intermediate member, said perforate partition consisting of a flat plate and being located on one side of the longitudinal center and entirely within said intermediate member.

8. A shell for a muffler, comprising, two like cylindrical end members each closed at one end and having an external flange on its free edge, said closed ends having reduced openings therein for the passage of exhaust gases and sound waves, an intermediate cylindrical member of like diameter between said end members, and an external circumferential flange at each end of said intermediate member to abut the flange on the respective end member, said flanges being joined to prevent separation of the members and to provide circumferential reinforcement for the shell, a flat perforate partition wall in the intermediate

member, and a perforate cup-shaped baffle in each end member.

9. A shell for a muffler, comprising, two like cylindrical end members each closed at one end and having an external flange on its free edge, said closed ends having reduced openings therein for the passage of exhaust gases and sound waves, an intermediate cylindrical member of like diameter between said end members, an external circumferential flange at each end of said intermediate member to abut the flange on the respective end member, said flanges being joined to prevent separation of the members and to provide circumferential reinforcement for the shell, and a baffle including a cylindrical wall portion in each end member, said cylindrical wall portion projecting inwardly from the closed end of the end member in which it is mounted being perforated and spaced from the circumferential wall of the end member in which it is mounted.

10. A muffler having an exterior cylindrical shell closed at its ends and having an inlet opening in one end and an outlet opening in the other end, a substantially centrally located perforated partition wall between said ends, and two oppositely facing substantially cup-shaped baffles including cylindrical portions concentric with the shell arranged in said shell, said two baffles being disposed one on each side of the partition.

11. A muffler having an exterior cylindrical shell closed at its ends and having an inlet opening in one end and a outlet opening in the other end, a substantially centrally located perforated partition wall between said ends, and two oppositely facing substantially cup-shaped baffles arranged in said shell one on each side of the partition, said cup-shaped baffles each consisting of a perforate cylindrical portion closed at the end disposed towards the partition and having an external imperforate flange at its other end.
